COMBINATION PAPER ROLL COVER AND UTILITY RECEPTACLE

Marjorie R. Basinais, 2692 11th St., Cuyahoga Falls, Ohio
Original design application Jan. 7, 1965, Ser. No. 83,328.
Divided and this application Aug. 26, 1965, Ser. No.
86,727

Term of patent 14 years

(Cl. D4—3)

FIG. 1

FIG. 3

FIG. 2

FIG. 4

FIG. 5

FIG. 1 is a front perspective view of a combination paper roll cover and utility receptacle showing my new design;

FIG. 2 is a cross-sectional view thereof, at one and one-half scale, taken on the line 2—2 of FIG. 1;

FIG. 3 is a cross-sectional view thereof, at one and one-half scale, taken on the line 3—3 of FIG. 1;

FIG. 4 is a bottom view thereof; and,

FIG. 5 is a rear perspective view thereof.

This application is a division of my co-pending application Serial Number D.83,328, filed January 7, 1965.

I claim:

The ornamental design for a combination paper roll cover and utility receptacle, as shown and described.
